UNITED STATES PATENT OFFICE.

HENRY PRICE BALL, OF BROOKLYN, NEW YORK, ASSIGNOR TO S. STERNAU & CO., A COPARTNERSHIP COMPOSED OF SIGMUND STERNAU & LIONEL STRASSBURGER, OF BROOKLYN, NEW YORK.

CONTAINER.

1,222,571.

Specification of Letters Patent.

Patented Apr. 10, 1917.

Application filed December 10, 1915. Serial No. 66,041.

To all whom it may concern:

Be it known that I, HENRY PRICE BALL, a citizen of the United States, resident of borough of Brooklyn, county of Kings, 5 city and State of New York, have invented a certain new and useful Container, of which the following is a specification.

This invention relates to improvements in containers or stoves for containing and burning solid fuel and has for its objects:

First: To combine a stove and container, said container being adapted to be used in different situations with stands or supports.

Second: To reduce the expense of manufacture.

Third: To prevent leakage due to expansion or contraction of the contents of the lamp.

These and further objects will more fully appear from the following specification and accompanying drawings, considered together or separately.

In the drawings—

Figure 1 is a plan view of a container embodying my invention;

Fig. 2 is a side view partly in elevation and partly in section of the same, said section being taken on the line 2—2 of Fig. 1;

Fig. 3 is a bottom view;

Fig. 4 is a plan view of a container embodying my invention combined with a stand;

Fig. 5 is a sectional view thereof taken on the line 5—5 of Fig. 4;

Fig. 6 is a side view, partly in section, of a container embodying my invention, combined with a different form of stand;

Fig. 7 is a plan view of still another form of stand, said container in this embodiment 40 of the invention being provided with a damper or regulator;

Fig. 8 is a sectional view on the line 8—8 of Fig. 7;

Fig. 9 is a sectional view on the lines 9, 9 45 of Fig. 10 of a container embodying my invention, which shows another form of stand; and

Fig. 10 is a side view of the same.

In all views, like parts are designated by 50 the same reference characters.

My improved container has a body 1. It is preferably made of sheet metal. This body is provided with a circular upper end 2. Adjacent to the edge of this end 2 is a 55 circular seat 3. This seat is adapted to re-

ceive a circular cover 4. The cover is adapted to make a close fit with the seat so that a tight joint will be produced and the cover will be held in place by friction. The cover is preferably provided with a circular flange 60 5 by means of which it may be removed. Within the body is a mass 6 of solid fuel. Preferably I employ what is known as "solid alcohol." The cover when in place prevents the escape and the evaporation of the alcohol. When it is removed the alcohol may be ignited and it will burn, the flame passing out through the circular seat 3. Preferably 65 this circular seat is made as large as possible so that an opening of the maximum size 70 is produced.

The sides of the container below the upper end are made non-circular. This non-circularity may be obtained by making a plurality of depressions 7 extending parallel 75 with the longitudinal axis of the container. These depressions may be of any number or shape, and, as shown, they extend from the bottom of the receptacle and do not extend beyond its upper edge. The length of these 80 depressions may be varied. Preferably they merge or taper into the cylindrical upper end of the body, as shown. The bottom of the container is preferably made with a circular depression 8, although such is not essential.

The body of the container may be made of a single piece of sheet metal, drawn or stamped to shape. The depressions 7 or other form of non-circularity may be made 90 at the time the body is being formed to its ultimate shape. Preferably the upper edge is made separately, as shown, but such is not essential.

This container is preferably made in small 95 sizes so that it may be employed for heating culinary articles, chafing dishes, coffee or tea pots and the like.

Figs. 4 and 5 show a useful adaptation of my improved container. A stand is formed 100 of sheet metal in two parts (a and b) which may, when not in use, be nested together and with the container. Each part is provided with a plurality of legs. In the center of each part is a circular opening, such opening being provided with fins or ears c. These fins or ears are equal in number to the depressions 7 of the body. By assembling the two parts of the stand as shown in Fig. 5 and inserting the container engage- 110

ment of the fins *c* with the depressions *7* will hold the three parts together. They will be locked particularly effectively together if the upper parts of the depressions taper or merge into the circular upper end of the container, as shown. The lamp being pushed into contact with the ears or fins will act with a wedge effect upon them, locking the parts together. Such a container and stand 10 form a rigid unitary structure and articles to be heated may be supported upon the legs of the part *a*.

Fig. 6 shows the utilization of my improved container with an improved stand. 15 In this stand the container is adapted to be raised or lowered so that the flame is brought into more or less intimate contact with the bottom of the utensil to be heated and the flame thereby regulated. This stand comprises a frame *d* having a plate *e* with a circular opening therein adapted to permit the container to pass through. This plate *e* is provided with fins or ears *e'* adapted to engage with the depressions *7* of the container. This will permit the container to be 20 raised or lowered, but not rotated. The container is supported within a pan *f*, said pan also having ears or projections which engage with one or more of the depressions 25 *7* so that this pan will not rotate. The pan is provided on its lower face with one or more cams *g*. These cams rest upon a bar *h* which is supported upon axis *i*, such axis being mounted upon the frame *d*. By rotating 30 the bar *h* the latter engaging with the cams *g* will raise or lower the pan *f* and with it the container, the depressions *7* of the latter preventing it from rotating.

Figs. 7 and 8 show a utilization of my invention in connection with a heat regulator. 40 In this utilization of the invention the container is supported upon a base *j*. This base is provided with one or more fins *k* adapted to enter one or more of the depressions *7* of the container and prevent it from being rotated. The upper part of the container is 45 provided with a ring *l*, upon which are mounted one or more dampers *m* by means of pivots *n*. These dampers are provided 50 with handles *o*, *o*, by means of which they may be turned upon the pivots. By opening or closing the damper the amount of heat given off by the container will be regulated. The engagement of the fin *k* with the depression *7* prevents rotation of the container 55 while the damper is being moved.

Figs. 9 and 10 illustrate a utilization of my improved container in connection with a folding stand. This stand is provided with 60 a plurality of legs *p* adapted to engage with the depressions *7* of the container. These legs are secured together by means of pivots *q* so that the stand may be folded. The engagement of the legs with the depressions *7* 65 of the container prevent the turning of the

legs upon their pivots with consequent collapsing of the stand. By making the legs snugly fit with the base of the depressions it is necessary that the stand be fully expanded before the container can be placed within it. For this reason it is impossible to introduce the container within the stand unless the latter is fully expanded and accidents caused by the container being introduced in the stand before the latter is fully 70 expanded are prevented.

Engagement of the container with the stand in the different utilizations I have illustrated, is an advantage in that the container will not rotate when in place, consequently a printed label containing instructions for operation, or the trademark or advertising matter, will always be correctly disposed in relation to the stand. It is of importance, in exhibiting stocks of goods, to 80 have the trademarks or labels on a number of containers all in the same position to produce the proper effect. It is also of service in using the container so that the printed instructions or warnings to the operator can 85 always be in the same position.

The depression *8* is of service in some situations in which the container may be employed, for example, in connection with the folding stand illustrated in my copending application for patent, Serial No. 878,879, although this depression is not essential. It frequently happens in use that the operator will extinguish the flame and replace the cover on the can before all of the 90 alcohol in the container has been consumed. This will be done while the parts are still hot, resulting in the alcohol continuing to be volatilized from the residual heat. This causes a considerable pressure within the 95 body of the can and thereby places strains on the various members of the can and on the joints. I overcome any deleterious results from this expansion and contraction by providing resilient means in the form of the 100 depressions *7* in the body, which permit the body to readjust itself to changes in expansion and contraction due to change in temperature, and thereby prevents leaks, 105 cracks or broken seams due to portions of 110 the body becoming fatigued locally.

Another advantage of the use of a grooved can is that should it be placed in proximity to a heated surface such as a radiator or a lamp there would be some parts of the can, 115 i. e. the bases of the grooves, somewhat removed from the heat and the contents would not melt as rapidly as if the grooves were not present.

When re-fills in the form of slugs or cartridges of solid alcohol are sold separate from the can, it is obvious that such re-fills cannot be equal in diameter to the greatest diameter of the can, but must be of a size to fit within the least diameter, that is within 125 130

the diameter bounded by the depressed portions and in order to get the proper quantity in the receptacle, the slug must be made taller than the can. When a slug is placed 5 within a can, and melted by the application of a gentle heat, the spaces between the depressions will be filled by the material which extended above to top of the can, and on solidifying will be of such a size and 10 shape that it cannot be withdrawn from the can.

In accordance with the provisions of the patent statutes, I have described the principle of my invention, together with the apparatus which I now consider to represent 15 the best embodiment thereof; but I desire to have it understood that the apparatus shown is merely illustrative and that the invention may be carried out in other ways.

Having now described my invention, what 20 I claim as new and desire to secure by Letters Patent, is:

As a new article of manufacture, a container adapted to carry a fuel and to be detachably secured to a suitable holder to constitute therewith a lamp, said container being formed of a material and constructed to resist damage thereof by heat, and a cover for normally inclosing the contents of the container adapted to be opened to expose a 25 flame opening, the body of the container being contoured to present approximately longitudinally disposed internal and external relatively raised and depressed portions, adapted to allow for expansion and contraction and constituting in part holder engaging means.

This specification signed and witnessed this ninth day of Dec., 1915.

HENRY PRICE BALL.
